UNITED STATES PATENT OFFICE.

ROBERT P. PEARSON, OF GLEN RIDDLE, PENNSYLVANIA, ASSIGNOR TO THE DUTCHER TEMPLE COMPANY, OF HOPEDALE, MASSACHUSETTS.

LOOM-TEMPLE.

SPECIFICATION forming part of Letters Patent No. 514,867, dated February 13, 1894.

Application filed August 12, 1893. Serial No. 483,010. (No model.)

To all whom it may concern:

Be it known that I, ROBERT P. PEARSON, a citizen of the United States, residing at Glen Riddle, in the county of Delaware and State 5 of Pennsylvania, have invented certain new and useful Improvements in Loom-Temples, of which the following is a specification.

My invention has relation to loom-temples for application to looms for weaving cloth or 10 other fabrics; and it relates more particularly to the construction and arrangement of a loom temple for such purposes.

The principal objects of my invention are, first, to provide a simple, durable, efficient 15 and inexpensive temple for application to looms adapted for weaving cloth and other fabrics; second, to provide a loom-temple so constructed and arranged as to be adjustable in connection with the breast-beam of 20 the loom to adapt the same to the required width of cloth being woven; third, to provide a loom-temple having an adjustable and detachable breast-beam slotted clamping device connected with a transverse support or holder 25 for the carrier of a pivotal-pod having an internal fixed roll provided with a revoluble perforated tube, the arrangement being such as that the temple may be set nearer to or farther from the reed, in order to adapt the same to 30 the requirements of a fabric being woven in the loom; fourth, to provide a loom-temple with an adjustable breast-beam clamp adjustably connected with a holder for a spring controlled detachable carrier provided with an 35 adjustable pivotal pod, in order that the same may be caused to assume required different positions with respect to the position of the shuttle race-board of the loom; fifth, to provide a loom temple with a vertically adjust- 40 able pivotal-pod and with a latch for locking the same to required position and with a slotted carrier provided with a spring controlled spindle detachably connected with a holder adjustably connected with a slotted breast- 45 beam clamping-device; sixth, to provide a loom-temple with an adjustable breast-beam clamping plate connected with a transverse slotted holder for an adjustable and detachable spring controlled pod-carrier having an 50 adjustable depending finger so arranged as to

permit of to and fro movement of the carrier in the operation of the loom; and seventh, to provide a longitudinally and horizontally adjustable and detachable loom temple adapted for employment in looms for weaving cloth 55 and other fabrics and so constructed and arranged as to perform the functions and purposes hereinafter fully described.

My invention consists of a loom-temple constructed and arranged for operation in substantially 60 the manner hereinafter described and claimed.

The nature, objects and general features of my invention will be more fully understood from the following description taken in connection with the accompanying drawings forming part hereof; and in which—

Figure 1, is a perspective view of a loom-temple embodying features of my invention. Fig. 2, is a similar view of the pivotal-pod of 70 my invention in an open position with the latch therefor released, and also showing the slotted carrier plate of the pod detached from its holder with its adjustable depending finger and the spindle thereof provided with a 75 spring coiled around the same. Fig. 3, is a similar view of the breast-beam slotted clamping-plate with its grooved or recessed seat for the reception of and for supporting the adjustable transverse holder for the pod carrier 80 plate of Fig. 2, by means of a securing device caused to engage said seat and the walls of the slotted portion of the holder. Fig. 4, is a similar view detached of the adjustable holder for the carrier plate of Fig. 2; and Fig. 85 5, is a transverse central section through the pivotal-pod in a closed position with the pivotal latch therefor in engagement with the cap thereof.

Referring to the drawings A, is the breast-beam clamping plate provided with an oblong slot a , in the body thereof for the reception of a threaded stud-bolt a' , for adjustably securing the same to the breast-beam of a loom. This clamping-plate A, is provided preferably 95 with integral depending fingers a^3 and a^4 , for engaging the surfaces or sides of the breast-beam of the loom, in order to prevent side-wise movement of the same while the plate A, is clamped thereto.

- a^5 , is a recessed seat formed integral with the clamping plate A, with end guides or projecting walls a^6 and a^7 , and with a projection a^8 , having a central threaded aperture therein.
- 5 B, is a holder or oblong plate provided with a loop b , a back-stop b' , and a bearing-post b^2 . This slotted holder or plate B, engages with the recessed seat a^5 , of the clamping plate A, with the loop extension b , thereof in engagement with the surface of the projection a^8 , and adjustably supported to position in contact with the ways or guides a^6 and a^7 , and projection a^8 , of the plate A, by means of a headed-screw or stud-bolt b^4 , and washer b^5 , thus affording the means, whereby the holder B, may be adjusted laterally with respect to the clamping plate A, as requirements demand in the weaving of a fabric in the loom.
- 10 C, is the pod-carrier plate provided with an oblong slot c , enlarged at one end as at c' , for admitting the back-stop or post b^2 , into the slotted portion c , of the carrier C.
- 15 At the outer end of the slotted portion of the carrier C, is provided a vertical projection or lug c^2 , having a horizontal spindle c^3 , formed preferably integral therewith and around which is coiled a spring c^4 .
- 20 c^5 , is a slot formed in the body of the carrier-plate C, beyond the oblong slot c , for the reception of the shank c^6 , of preferably a depending recessed finger c^7 , which is secured to position in said slot c^5 , by means of a bolt and nut c^{10} . This adjustable finger c^7 , affords 25 the means whereby a movable member of the loom by being actuated may be brought into engagement with said finger so as to permit of the reciprocation of the pod-carrier plate C, in a forward direction either rapidly or slowly according to the location of the finger c^7 , and in such manner as that it may be returned to its initial position by the force of the coiled spring c^4 , of the spindle c^3 , of the carrier plate C, for enhancing the effective 30 action of the temple in its connection with a loom of the type in which such devices are employed for maintaining the cloth or other fabric taut during the weaving thereof.
- 25 D, is the pod comprising a bottom trough d , with integral vertical projecting lugs d' and d^2 , and with an angular slotted heel piece d^3 , which engages by means of a tightening screw or bolt d^4 , with the recessed end c^9 , of the carrier plate C, provided with a recessed seat c^{11} , for the head d^5 , of the bolt d^4 .
- 30 d^6 , is the cap of the pod pivotally connected with the lips or lugs d' and d^2 , and provided with a rigidly secured roll d^7 , detachably connected to a rear depending tongue d^8 , formed 35 preferably integral with the wall of the cap d^6 , by means of a stud-bolt d^9 , with a metal washer d^{10} , applied thereto. Around the roll d^7 , is mounted a perforated or grater like surfaced tube or cylinder d^{11} , for enabling the 40 fabric to be firmly nipped and held while the same is being woven and preparatory to the same being conveyed onto the cloth roll of the

loom, not shown, for permitting subsequently of the removal of the completed fabric from the loom.

70 d^{12} , is a latch pivotally connected with the heel-piece d^3 , and adapted to be brought into engagement with the recessed face d^{13} , of the pod-cap d^6 , for firmly holding the revoluble perforated and roughened surface tube d^{11} , of the pod D, into contact with the cloth, as well as affording the means to permit of the ready release of the perforated tube of the cap from the cloth upon the release of the latch from its seat d^{13} , in the surface of the cap d^6 , as hereinbefore described and as fully illustrated in Figs. 1 and 2. The slotted heel piece d^3 , affords the means through the intervention of the tightening screw engaging the walls thereof, whereby the pivotal pod may be adjusted vertically with respect to the carrier-plate C, in order to compensate for requirements of the temple with respect to the type of loom in which it is employed.

75 The carrier plate C, with its oblong slot c , presents the means, whereby in the event of it becoming necessary to rip out the warp or to insert a rod when the end of the warp has been reached in the loom, the pod-carrier plate C, may be readily removed from its engagement with the back-stop b' , of the holder plate B, through the enlarged end of the slotted portion of said plate, for such purposes as well as others, and which will be readily understood by those skilled in the art to which my invention appertains, without further explanation.

80 It will be manifestly obvious that as to minor details modifications may be made without departing from the spirit of my invention.

85 Having thus described the nature and objects of my invention, what I claim as new, and desire to secure by Letters Patent, is—

1. A loom temple provided with a breast beam clamping plate having a slotted body, depending fingers and a recessed seat provided with a projection with a threaded opening therein, a holder provided with a loop adapted to engage the projection of said plate, a back-stop and bearing post, a spring controlled carrier provided with a pod and a depending finger, substantially as and for the purposes set forth.

110 2. A loom temple provided with a breast beam clamping plate having a slotted body, depending fingers and a recessed seat provided with a projection, a slotted holder adapted to engage the projection of said plate and adjustable with respect to the plane of said clamping plate and supporting a carrier 115 or plate having a pod, and a depending finger, substantially as and for the purposes set forth.

120 3. A loom temple provided with a breast beam clamping plate having depending fingers, a slotted holder engaging said plate and provided with a bearing post and back-stop, a slotted carrier plate provided with an adjustable depending finger and with a spindle

having a spring coiled around the same for returning said plate to initial position upon release of said finger from contact with a movable member of the loom, a pivotal and vertically adjustable pod connected with said carrier-plate and having a fixed roll with a revoluble perforated or grater-like tube and a latch adapted to engage said pod, substantially as and for the purposes set forth.

5 4. A loom temple provided with a breast beam clamping-plate having lugs forming ways and with a projection, a slotted holder held to the projection of said clamping-plate by a tightening-screw, a slotted carrier plate provided with a spring controlled spindle and a depending finger adapted to engage a movable member of the loom to move said carrier plate and returned to its initial position by the spring of said plate, an adjustable pod

10 provided with a latch for engaging the same, and a roll mounted in said pod and provided with a perforated tube or shell, substantially as and for the purposes set forth.

15 5. A loom temple provided with a breast beam clamping plate having a recessed seat with a projection, a holder provided with a loop, a back-stop and a bearing post, a slotted

carrier provided with a depending finger, a controlled spindle and an adjustable pod provided with a roll having a perforated tube or shell, and a latch for closing said pod, substantially as and for the purposes set forth.

6. A loom temple provided with a breast beam clamping plate with depending fingers, a recessed seat and a projection, a slotted holder detachably engaging with said projection and said holder provided with a back-stop and a bearing post, a spring controlled spindle connected with a carrier plate having a vertically adjustable pod comprising two hinged members, whereof one has journaled thereto a roll with a perforated and grater like surfaced shell and a recessed latch adapted to engage a complemental recess in one of the members of said pod, substantially as and for the purposes set forth.

In testimony whereof I have hereunto set my signature in the presence of two subscribing witnesses.

ROBERT P. PEARSON.
